UNITED STATES PATENT OFFICE.

MARGARET ANN GUINAN, OF HUDSON, NEW YORK.

GARMENT.

1,122,737.

Specification of Letters Patent. Patented Dec. 29, 1914.

Application filed August 29, 1913. Serial No. 787,327.

To all whom it may concern:

Be it known that I, MARGARET ANN GUINAN, a citizen of the United States, residing at Hudson, in the county of Columbia and State of New York, have invented 5 certain new and useful Improvements in Garments, of which the following is a specification.

My invention relates to garments for 10 feminine wear, particularly to underskirts, and has for its object the provision of a garment of this character which is formed from a single piece of material without the necessity of gores and seams, and which 15 may be quickly and easily applied and adjusted to fit widely different figures or changes in an individual figure, and which will fit snugly and smoothly around the waist and hips, thus avoiding "bunching" 20 or an undesirable degree of fullness.

An important object is to provide a garment of this character which is of sufficient width that when applied to a figure, the edges will overlap and form a double thickness to prevent the wearer's limbs from being 25 visible in case a gown of thin material is worn.

Other objects and advantages such as simplicity, efficiency, durability, ease of applying and removing, economy in manufacture 30 and the general improvement of the art will be brought out in the following specification and illustrated in the accompanying drawing, in which:

Figure 1 is a perspective view of a portion 35 of a figure showing method of attaching my improved skirt, Fig. 2 is a similar view showing the skirt applied, and Fig. 3 is a view of the skirt removed and flattened out 40 to show the structure.

Referring more particularly to the drawings, the numeral 1 designates the body of the skirt which has its upper and lower ends 2 and 3 formed arcuate, as shown, and its 45 side edges 4 and 5 formed straight. The top end 2 may be finished in any desired manner as by stitching on a narrow binding 6. The bottom end 3 may be finished as by stitching on any suitable trimming as for 50 instance the ruffle 7, but the edges 4 and 5 should be bound with tape which is on the straight as opposed to the cloth which is on the bias.

In order to shape the upper portion of the 55 skirt to the wearer's waist and hips, a plurality of darts 8 are provided. An addi-

tional dart 9 formed on the line of the hips prevents bagging and sagging of the skirt.

The skirt is adapted to be secured upon the wearer by means of tapes or strings 10 which are secured upon the upper corners of the skirt, as shown, and which are to be tied around the waist. A loop 11 is secured upon the edge 4 at the hip line and is adapted to be engaged by a tape or string 12 also 60 secured upon the skirt at the hip line intermediate the side edges 4 and 5, as shown at 13, for a purpose to be described.

Secured upon the skirt adjacent the edge 5 at the hip line is a button 14 adapted to 65 engage the button holes in a button hole tape 15 stitched in alignment therewith adjacent the edge 4. At a point some distance above the bottom end 3 of the skirt and adjacent the edge 5 is a second button 16 70 adapted to engage the button holes in a button hole tape 17 stitched in alignment therewith upon the skirt adjacent the edge 4.

The skirt is applied by placing it upon 75 the figure with the edge 4 in the back, as shown in Fig. 1, then bringing the edge 5 over the edge 4 so that they overlap, and then bringing the tapes 10 around the waist 80 and tying them in front. The tape 12 may then be passed through the loop 11, whereupon a pull upon the tape 12 will cause the skirt to conform closely to the hips. The button 14 may then be inserted within the proper one of the button holes in the tape 15 for securing the skirt snugly upon the figure. The button 16 may then be inserted 85 within a selected one of the button holes in the tape 17 for holding the lower portion of the skirt and also allowing the desired 90 amount of fullness, as shown in Fig. 2.

From the foregoing it will be seen that 95 the skirt may fit snugly around the hips while the bottom portion may be either very tight, very full, or have any desired intermediate degree of fullness. The fact that the button 16 and button hole tape 17 are above the bottom end 3 shows that great freedom of movement of the feet may be had even though the skirt may be tight. It will also be noted that the darts 8 and 9 give the skirt the proper curvature at its upper portion to prevent bagging, sagging or "bunching."

By having the edges 4 and 5 overlapping 110 sufficient thickness of material is provided for preventing the wearer's limbs from be-

ing visible through a thin gown even though no additional underskirt is worn.

It will be understood that I may use hooks and eyes, snaps, loops or any other suitable fastening means in place of the buttons and button holes, and that I may adapt the skirt to have its overlapping ends at the front or at either side instead of in the back.

10 As is well known in the art and to the trade, the common style of underskirt is formed of a plurality of gores with a corresponding number of long seams, and such an underskirt will fit only a figure of a certain size, which necessitates manufacturers making and dealers carrying in stock a large number of sizes, whereas from the drawings and the foregoing description it is apparent that I have not only provided 15 an underskirt which fits smoothly and snugly, and allows of freedom of movement, and which may be adjusted to fit any figure, but also an underskirt which renders it unnecessary to manufacture a number of 20 different sizes and which saves the dealers the expense of carrying so large a stock as is necessary with the old style of underskirt where they must be prepared to meet demands for different sizes.

30 Having thus described my invention what I claim is:

1. An adjustable underskirt formed in one piece comprising a waist portion, a hip portion and a lower portion, a tape for adjusting said waist portion mounted thereon, 35 darts formed at the waist line for shaping

the skirt to the hips of the wearer, adjustable means for securing the skirt around the hips, and adjustable means for giving the lower portion of the skirt the desired fullness; said skirt being adapted to be open its full length at the back and have its edges overlap when on the wearer.

2. An adjustable underskirt formed in one piece comprising a waist portion, a hip portion and a lower portion, a tape for adjusting said waist portion mounted thereon, darts formed at the waist line for shaping the skirt to the hips of the wearer, a button on one edge of the skirt at approximately 40 the hip line, a tape secured at one end on said line near said button, a strip having a plurality of button holes therein secured on said line adjacent the opposite edge of said skirt, and a loop secured on said line at 45 said last mentioned edge, a button secured to the lower portion of said skirt adjacent the first mentioned edge thereof and a strip having a plurality of button holes secured on said lower portion adjacent the edge opposite to the last mentioned edge and approximately on a line with said last mentioned button; said buttons being adapted 50 for engagement with selected holes of said strips, respectively.

In testimony whereof I hereto affix my signature in the presence of two witnesses.

MARGARET ANN GUINAN.
